UNITED STATES PATENT OFFICE

169,512

COMBINATION CLOCK, RADIO, AND PIANO
CASINGMax Liffmann, Providence, and Nicholas Turilli,
Cranston, R. I.

Application May 29, 1952, Serial No. 19,946

Term of patent 3½ years

(Cl. D56—9)

To all whom it may concern:

Be it known that we, Max Liffmann and Nicholas Turilli, both citizens of the United States, residing at Providence and Cranston respectively, in the county of Providence and the State of Rhode Island, have invented a new, original, and ornamental Design for a Combination Clock, Radio, and Piano Casing, of which the following is a specification, reference being had to the accompanying drawing, forming part thereof.

The single figure is a perspective view of a combination clock, radio, and piano casing showing our new design.

The unshown side is like the side shown, and the back is plain.

We claim:

The ornamental design for a combination clock, radio, and piano casing, as shown and described.

MAX LIFFMANN.
NICHOLAS TURILLI.
